BUTTON SEWING MACHINE.
APPLICATION FILED AUG. 3, 1916.

Patented Sept. 25, 1917.
2 SHEETS—SHEET 2.

UNITED STATES PATENT OFFICE.

WILLIAM L. BARRON, OF NEW YORK, N. Y., AND FRITZ E. OSOL, OF ELIZABETH, NEW JERSEY, ASSIGNORS TO THE SINGER MANUFACTURING COMPANY, A CORPORATION OF NEW JERSEY.

BUTTON-SEWING MACHINE.

1,240,921.

Specification of Letters Patent. Patented Sept. 25, 1917.

Application filed August 3, 1916. Serial No. 112,906.

To all whom it may concern:

Be it known that we, WILLIAM L. BARRON and FRITZ E. OSOL, citizens of the United States, residing, respectively, at New York, 5 in the county of New York and State of New York, and Elizabeth, in the county of Union and State of New Jersey, have invented certain new and useful Improvements in Button-Sewing Machines, of which 10 the following is a specification, reference being had therein to the accompanying drawings.

This invention has for its object to provide a button-holder adapted to rigidly hold 15 a button while being secured to a garment by means of fastening stitches, but constructed to permit easy introduction and removal of the button.

As preferably constructed, the button-holder is secured to a spring-pressed presser-bar of a sewing machine and comprises two levers, provided with button-gripping 20 jaws connected together for reciprocal movement. A button-jaw setting device is provided with a clearance aperture permitting sufficient movement of the clamping levers for easy insertion or removal of a button, a spring tending to force the button-clamping 25 jaws toward each other within the limits 30 of such movement. It has been found in practice, however, that a large-size button must be rigidly held during the sewing operation, and accordingly the present clamp is provided with a locking device adapted 35 to normally prevent the action of the spring and thereby rigidly hold the button during the sewing operation. This locking device may be manually released in the lowered position of the button-holder and is mechanically released when the button-holder 40 is lifted for removal and insertion of the work.

In the accompanying drawings, Figure 1 is a side elevation and Fig. 2 a front end 45 elevation of a button sewing machine embodying the present invention. Fig. 3 is a top plan and Fig. 4 a bottom plan of the button-holder. Figs. 5, 6 and 7 are detail perspective views of detached parts of the 50 button-holder. Figs. 8 and 9 are detail perspective views of the clamping-lever setting and locking devices.

The machine as shown is constructed with a frame comprising a hollow standard 1 55 with the lateral work-sustaining arm or

horn 2 and the hollow overhanging arm 3 in which latter is journaled the main-shaft 4 carrying at its rearward end the fast and loose pulleys 5 and 6 and at the forward end the take-up cam-cylinder 7. This cam-cylinder is provided with a crank-pin 8 connected by means of the pitman 9 with the usual stud upon the collar 10 fixed upon the needle-bar 11 which carries the eye-pointed needle 12. The reciprocating needle-bar 11 is journaled in the swinging frame 13, fulcrumed within the head of the bracket-arm and provided with a lateral arm 14 operatively connected by means of a link 15 with a lateral arm 16 of a rock-shaft 17. The rock-shaft 17 carries another arm 18 having a roller-stud 19 entering a cam-groove 20 formed in a cam-wheel 21 shown partly in section in Fig. 2. The cam-wheel 21 is carried by a transverse shaft 22 suitably rotated 75 from the main-shaft 4 by means of a worm-wheel 23 and worm 24.

The shaft 22 also carries a stop-motion controlling cam 25, shown in Fig. 1 partly in full and partly in dotted lines. The periphery of the controlling cam 25 contacts with a roller-stud 26 carried by a bellerank-lever 27, fulcrumed at 28 upon the frame 1 of the machine and suitably connected with an ordinary form of stop-motion device.

Coöperating with the needle 12 is the oscillating shuttle 29 journaled in the race 30 and provided with the thread-case 31. The shuttle is actuated by means of the driver 32 at the forward end of the rock-shaft 33 mounted within the horn 2 and having at its rearward end the crank 34 actuated in a well-known manner by means of the pitman 35 connected with the crank 36 of the 95 main-shaft 4.

The lateral arm or horn 2 is provided with a raised work-supporting portion 37 and opposed thereto is the presser-foot 38 adapted to rest upon the fabric *m* and secured by means of screws 39 to the vertical presser-foot carrying bar 40 slidingly mounted in a guideway 41 of a bracket 42 secured to the frame of the machine.

The presser-bar 43 is journaled in the head of the bracket-arm and has adjustably secured thereto by means of the set-screw 44 the collar 45, having a forked arm 46 embracing the guide-rod 47 and the upwardly projecting arm 48 having a lateral lug 49 110

adapted for engagement by the forward arm 50 of a lifting lever mounted upon the fulcrum screw-stud 51 sustained by the frame. The lifting lever has a rearwardly extending arm 52 and pivoted thereto by means of a screw 53 is a link 54 to which is attached a rod 55 having suitable connection with a treadle. Surrounding the presser-bar 43 is a spring 56 interposed between the collar 45 and the upper bearing of the bar.

Secured to the lower end of the pressure-bar 43 by means of the screw 57 is the shank 58 of the laterally extending frame-plate 59 formed with a slot 60 through which passes the shank of the thumb-screw 61 by means of which is adjustably secured in place the plate 62 sustaining the operative parts of the button-holder. The plate 62 carries a guiding screw 63 entering a slot 64 in the frame-plate 59 and is formed at its rearward end with threaded apertures 65 entered by the fulcrum-screws 66 of the clamping levers 67 and 68 provided with button-gripping jaws 69 and 70. The clamping levers 67 and 68 are connected for reciprocal movement by means of the pivot-block 71, carried by the lever 68 and embraced by the fork 72 of the lever 67. A spring 73 has its opposite ends connected with the clamping levers by means of screws 74 and tends to draw the jaws 69 and 70 toward each other.

Fulcrumed upon a screw-stud 75 depending from the holder-plate 62 is an angle-lever formed with arms 76 and 77, the latter of which is formed at one end with a boss 78 provided with a threaded aperture to receive the shank 79 of an adjusting clamp-screw 80 passing through a slot 81 in the holder-plate 62. The end of the other arm 76 carries a screw-pin 82 embraced by one apertured end of a link 83 formed with an elongated aperture 84 and with depending lugs 85 and 86. One side of the lug 86 is inclined to provide a trapezoidal opening entered by the wedge-block 87 constituting a detachable section of the link 83 and carried by one end of a rod 88 which passes through the elongated aperture 84 in the link and through the hollow post 89 carried by the clamping lever 68. The post 89 extends upwardly through a slot 90 in the holder-plate 62. A spring 91 surrounds the post 89 and is interposed between the clamping lever 68 and a collar 92 on the upper end of the rod 88 and tends to retain the wedge-block 87 seated upon the bottom or inclined side-wall of the trapezoidal opening in the link 83. The clamp-screw 80 may be adjusted in the slot 81 so as to swing the angle-lever 76, 77 on its fulcrum and set the button-jaws 69 and 70 for a button of the desired size. When the jaws are set in this manner, the wedge-block securely holds the clamping levers during the lowered po-

sition of the button-holder. When the wedge-block 87 is seated in the opening between the lugs 85 and 86, it acts as a locking device to take up the lost-motion provided by the slot 84 and to thereby rigidly hold the clamping levers against movement, this being the normal position of the wedge-block during the sewing operation. The operator, however, can readily press on the collar 92 in the lowered position of the button-holder, thereby unseating the wedge-block from its recess and permitting movement of the clamping levers against the action of the spring 73 within the limits of the slot 84 in the link 83. Means are thus provided in the lowered position of the button-holder permitting the release of the rigid gripping jaws for adjusting the button or for other purposes.

Provision is also made for mechanically depressing the wedge-block carrying rod 88. As previously described, the button-holder is secured to the presser-bar 43 and can accordingly be raised by treadle connection with the lifting lever 50, 52. As the button-holder approaches its extreme upper position in the lifting movement, the wedge-block carrying rod 88 abuts against the plate 93 secured to the lower end of the rod 47 and the wedge-block 87 is depressed and thus detached from the link 83 to permit the clamping levers 67 and 68 to yield sufficiently against the action of the spring 73 for ready removal of the button 3, from the jaws 69 and 70 and insertion of another button 100 therein. When the button-holder is again lowered preparatory to a sewing operation, the wedge 87 is reseated by the spring 91 and causes the slotted link 83, of which it forms a section, to hold the button-gripping jaws 105 69 and 70 rigid until released, as described.

Having thus set forth the nature of the invention, what we claim herein is:

1. A button-holder for sewing machines comprising clamping members having opposed gripping jaws, a locking device adapted to normally prevent movement of the clamping members toward or from each other, button-holder lifting means, and means operable independently of said lifting means for rendering said locking device ineffective.

2. A button-holder for sewing machines comprising gripping jaws, a gripping-jaw locking device, button-holder lifting means, and means separate from said lifting means for releasing said locking device when the button-holder is lifted.

3. A button-holder comprising opposed gripping-jaws, a gripping-jaw setting device, and a locking connection between said setting device and said jaws and movable relatively to and independently of said jaws.

4. A button-holder comprising opposed gripping-jaws connected for reciprocal

- movement, a gripping-jaw setting device, and a locking connection between said setting device and one of said jaws and movable relatively to and independently of said 5 jaw. 5. A button-holder for sewing machines comprising opposed gripping jaws, a gripping-jaw setting device, means connected with said setting device for locking said 10 jaws against movement toward or from each other, button-holder lifting means, and means for releasing said jaws when the button-holder is lifted. 6. A button-holder for sewing machines 15 comprising opposed gripping jaws, means for setting said jaws in spaced relations for different sizes of buttons, a spring adapted to force said gripping-jaws to yieldingly hold a button, button-holder lifting means, 20 and means independent of said lifting means and of said setting means for normally rendering the action of said spring ineffective. 7. A button-holder for sewing machines 25 comprising opposed gripping jaws, a spring adapted to force said gripping jaws to yieldingly hold a button, a locking device for normally rendering the action of said spring ineffective, button-holder lifting means, 30 means, and means separate from said lifting means for rendering said locking device ineffective when the button-holder is lifted. 8. A button-holder for sewing machines comprising opposed gripping-jaws connected 35 for reciprocal movement, a spring adapted to force said gripping-jaws into holding relation with a button, means for locking said jaws against reciprocal movement, button-holder lifting means and means independent 40 of said lifting means for releasing said locking means. 9. A button-holder comprising a support, clamping members sustained by said support and having opposed gripping-jaws 45 movable toward and from each other, means for setting said jaws in spaced relations for different sizes of buttons, and a locking connection between said setting means and the 50 jaws to prevent relative movement of the jaws during the sewing operation. 10. A button-holder comprising a support, clamping members sustained by said support and having opposed gripping-jaws movable toward and from each other, means for setting said jaws in spaced relations for 55 different sizes of buttons, a locking connection between said setting means and the jaws to prevent movement of the jaws during the sewing operation, and means for releasing said locking connection to permit 60 limited movement of the jaws for insertion and removal of buttons. 11. A button-holder comprising a support, clamping members sustained by said support and having opposed gripping-jaws 65 movable toward and from each other, means for setting said jaws including a lever fulcrumed on said support, and a locking connection between said lever and one of said clamping members. 12. A button-holder comprising a support, clamping members sustained by said support and having opposed jaws movable toward and from each other, means for setting said jaws including a lever fulcrumed 70 on said support, a locking connection between said lever and one of said jaws, and means for releasing said locking connection to permit limited movement of said jaws. 13. A button-holder comprising opposed 75 gripping-jaws, a gripping-jaw setting device including a link formed in relatively movable sections, and means normally acting to unite said sections to rigidly hold the jaws in their set positions. 14. A button-holder comprising opposed 80 gripping-jaws, a gripping-jaw setting device including a link formed in relatively movable sections, means normally acting to unite said sections to rigidly hold the jaws 85 in their set positions, and means for relatively shifting said sections.

In testimony whereof, we have signed our names to this specification.

WILLIAM L. BARRON.
FRITZ E. OSOL.
